UNITED STATES PATENT OFFICE.

LEONARD L. GUGEL, OF LOUISVILLE, KENTUCKY.

FOUNTAIN-PEN.

1,277,064.

Specification of Letters Patent. Patented Aug. 27, 1918.

Application filed December 8, 1917. Serial No. 206,241.

To all whom it may concern:

Be it known that I, LEONARD L. GUGEL, a citizen of the United States, residing at Louisville, in the county of Jefferson and State of Kentucky, have invented certain new and useful Improvements in Fountain-Pens, of which the following is a specification.

This invention relates to fountain pens and has for its object the production of a simple and efficient fountain pen having a plurality of ink containing compartments for the purpose of containing different color inks and permitting a user to write with different color inks merely by changing the position of the pen in his hand.

Another object of this invention is the production of a pen which is provided with means for separating the pen points when the pen is not in use, and in this way preventing the smearing of ink from one pen point to the other.

With these and other objects in view this invention consists of certain novel constructions, combinations and arrangements of parts as will be hereinafter fully described and claimed.

In the drawings:

Figure 1 is a longitudinal section through the fountain pen.

Fig. 2 is a section taken on line 2—2 of Fig. 1.

Fig. 3 is a transverse sectional view through the pen point gripping end of the pen, taken on line 3—3 of Fig. 1, the closure cap being removed.

Fig. 4 is a transverse sectional view through the pen point gripping end of the pen, the section being taken across the indicating band, taken on line 4—4 of Fig. 1, the closure cap being removed therefrom.

Fig. 5 is a section taken on line 5—5 of Fig. 1.

Fig. 6 is a section taken on line 6—6 of Fig. 1.

Fig. 7 is a side elevation of the outer end of the pen with the cap removed.

By referring to the drawings, it will be seen that 1 designates the body of the pen which constitutes a tube having an internally threaded end 2. This tube or body 1 is provided with a centrally located longitudinally extending partition 3 as shown in Figs. 1 and 6 of the drawing, for producing an ink containing compartment 4 and an ink containing compartment 5. This partition

3 terminates short of the outer end of the tube or body 1, as shown clearly in Fig. 1 of the drawing.

A point supporting cap or end is provided with an externally threaded end 7 which threads into the internally threaded end 2 of the tube or body 1. This pen point supporting cap or end 6 is provided with a centrally located longitudinally extending partition 8 as shown in Figs. 1 and 5 for producing an ink channel 10 and an ink channel 11. A pen point retaining plug 12 is mounted within each channel 10 and 11 and is adapted to firmly clamp and support a pen point 13. The pen points which are mounted within the channels 10 and 11 are placed with their convex faces toward each other as shown clearly in Figs. 1 and 3 of the drawings. These pen points 13 are of substantially the same length and while the pen is being used, the tube or body 1 will naturally extend on an incline with respect to the surface upon which the pen is writing, thereby causing only one of the pen points 13 to come into contact with the writing surface.

An indicating band 14 is formed around the pen point supporting cap 6 and is embedded therein as shown in Fig. 1 for the purpose of causing the outer face of the indicating band 14 to extend flush with the outer face or side of the cap 6. This indicating band 14 may be formed or divided in two colors or may have an indicating legend 15 formed diametrically opposite upon the respective side faces of the band 14. A truing pin 16 is carried by the tube or body 1 and is adapted to register with a truing pin 17 carried by the cap 6 for the purpose of indicating to the user that the channels 10 and 11 are in proper registration with the compartments 4 and 5. The partition 8 is adapted to abut against the end of the partition 3 as shown in Fig. 1 when the truing pins 16 and 17 register, in this way preventing the leaking of the ink from one compartment to another and also prevent the leaking of the ink from the tube 1. It of course should be understood that the pen point retaining plugs 12 are provided with suitable feeding apertures 18 for feeding ink from the channels 10 and 11 to the pen points 13.

A closure cap 19 is adapted to fit over the cap 6 and this closure cap 19 is provided with a longitudinally extending centrally

arranged partition 20 which partition tapers toward its inner end 21, the inner end 21 being adapted to fit between the respective pen points 13 and prevent the ink from flowing from one point to the other while the pen is not in use. The tapering nature of the partition 20 will assist in placing the cap 19 over the outer end of the pen point supporting cap 6 as will be obvious by considering Fig. 1. This partition 20 however, terminates short of the open end of the closure cap 19 for the purpose of permitting the closure cap to be placed over the inner or upper end of the body or tube 1, while the pen is in use. Suitable vent apertures 22 are formed in the outer end of the closure cap 19 and communicate with the respective compartments 23 and 24 formed in the closure cap 19.

20 The present invention is especially adapted for use where it is necessary to use two different color inks. By use of the present device, it should be understood that blue ink may be placed in the compartment 4 and red ink may be placed in the compartment 5. The operator or user may in this manner use either red or blue ink merely by rotating the body 1 within his hand and using the desired point of the pen. In this way the user will not be likely to confuse the colors of the ink or mix the same in view of the fact that the indicating band 14 will readily indicate to the user the kind of ink which is being used. The user will not be compelled to lay down one pen and pick up another but will be provided with a fountain, self feeding pen supporting or containing several different kinds of ink.

What is claimed is:—

40 1. A pen of the class described comprising a tube, said tube provided with a plurality of compartments, a cap detachably

supported upon said tube and provided with channels registering with said compartments, a pen point carried within each channel, a plug mounted within each channel, a closure cap detachably engaging said first mentioned cap, said closure cap provided with a partition, tapering toward the inner end thereof, said partition adapted to fit between said pen points, and said partition terminating short of the inner end of said closure cap.

2. A pen of the class described comprising a tube, said tube provided with a plurality of compartments, a cap detachably supported upon said tube and provided with channels registering with said compartments, a pen point carried within each channel, a plug mounted within each channel, a closure cap detachably engaging said first mentioned cap, and means mounted within said closure cap and adapted to separate said pen points and prevent contact thereof with each other while said closure cap is in a closed position upon said first mentioned cap.

3. A pen of the class described comprising a tube provided with a plurality of pen points supported thereon, a detachable cap mounted upon said tube and adapted to constitute a closure therefor, and means formed within said detachable cap and fitting between said pen points for holding the same in spaced relation and preventing the flowing of ink from one point upon the other point.

In testimony whereof I affix my signature in presence of two witnesses.

LEONARD L. GUGEL
